UNITED STATES PATENT OFFICE.

LUCY J. TRIPP AND FRANK M. ENOS, OF ROCHESTER, NEW YORK, EXECUTORS OF JAMES SMITEN TRIPP, DECEASED.

HOOK AND HOLDER FOR EXTENSION-LADDERS.

SPECIFICATION forming part of Letters Patent No. 755,190, dated March 22, 1904.

Application filed July 10, 1903. Serial No. 164,984. (No model.)

To all whom it may concern:

Be it known that JAMES SMITEN TRIPP, deceased, late a citizen of the United States, and a resident of Rochester, Monroe county, New York, of whose estate LUCY J. TRIPP and FRANK M. ENOS, citizens of the United States, and residents of Rochester, Monroe county, New York, are executors, did invent new and useful Improvements in Hooks and Holders for Extension-Ladders, of which the following is a specification.

This invention relates to certain improvements in automatic locking devices for the sliding sections of extension-ladders and in means for connecting same with a ladder-rail.

The improved locking device and holder are of such construction as to permit of their being connected with either or both rails of a ladder, as is hereinafter fully explained, so that the ladder may be lengthened or shortened, as desired.

Referring to the drawings, Figure 1 is a perspective view of two ladder-sections and the locking device. Fig. 2 is a perspective view from the inner side of the locking-device holder. Fig. 3 is a side view of the locking device and holder. Fig. 4 is a rear view of the locking device, and Fig. 5 an edge view of the trip-latch.

On the drawings, the letters A B designate two sections of an extension-ladder, and C C' the rungs thereof.

The locking devices and holders are intended to connect with the sliding section of the ladder and either used single or in pairs. Thus for light work there is employed but one locking device and holder, the same being secured to either the right or left rail of the sliding section, while for heavy ladders one is applied to each rail in such manner that their hooks may engage the same rung of the ladder-section beneath same.

The holder D consists of a T-shaped plate, the top members of which are each provided with stop-arms c c' and the lower member with a bolt-opening F and a bearing-plate g. The stop-arms and bearing-plate are of equal lengths and each is provided with a point for penetrating the ladder-rail, and thus the said

plate adjusts itself parallel with the side of the rail.

The locking device H consists of a pivotal bar z, having a rearwardly-projecting eye z' at its lower end and having near its upper end a hook portion k for engaging the rungs of a ladder. A curved slide l extends upward and rearward from the point of the hook, and a lug m is formed in rear of the hook-recess. This lug and a portion of the locking-bar below same is provided with a central slot or opening n, within which the trip-latch O is suspended by a pin p, so that the front end of the trip-latch may when swung forward strike against the point of the hook. The trip-latch has a curvilinear edge and provided at its forward end with side pins q q' to prevent its being forced out of the locking-bar slot when impelled backward. To strengthen the upper part of the locking-bar, the rear of the slide and hook is provided with a central rib r, which terminates in the lug at the back of the hook, as clearly shown in the drawings.

In the application of the improvements to ladders the holder D is first placed in the desired position with its points against the inside of the rail of the sliding ladder-section. By pressure the points are embedded in the rail and the T-plates assume a position parallel with the surface of the rail. The lower end of the locking device is then passed downwardly between the stop-arms of said plate with the hook inclined toward the rungs of the ladder. A suitable bolt is next inserted into the hole of the plate and eye of the locking-bar. The end of the bolt is then screwed into the ladder-rail or passed through a hole therein and is thus secured either by a screw-nut or any other well-known means for so doing. To insure the pressing forward of the hook, a spring t is connected with the holder-stud, in the rear thereof, as shown in Fig. 3 of the drawings.

Having described the invention, what is claimed as new, and desired to be secured by Letters Patent, is—

1. In extension-ladders, a hook-supporting frame comprising a T-shaped plate, the upper members of the plate provided with stop-arms and the lower member with a bolt-opening and

a bearing-plate, the stop-arms and bearing-plate of equal lengths; the stop-arms provided with points to engage the rail, substantially as set forth.

- 5 2. In extension-ladders, a hook-supporting frame comprising a T-shaped plate, the upper members of the plate provided with stop-arms, and the lower member with a bolt-opening and a bearing-plate, the stop-arms and bearing-plate of equal lengths and each provided with points, whereby in applying the plate to the side of a ladder-rail, the said plate will adjust itself parallel therewith, substantially as set forth.
- 10 3. In extension-ladders, the combination of a T-shaped holder provided at one side with a pair of stop-arms and a bearing-plate each having a pointed end, a bolt-opening in the lower member of the plate, a bolt adapted to fit there-

in to secure the plate to the rail and at the same time serve as a bearing for the locking-bar, with a locking-bar having an eye at its lower end, and a hook with a curved slide at its upper end, the locking-bar provided with a central opening, and a rib with an intermediate lug, and a trip-lever pivotally connected with the lug, substantially as and for the purpose set forth.

In testimony whereof we have hereunto set our hands this 11th day of June, A. D. 1903. 30

LUCY J. TRIPP,
FRANK M. ENOS,

*Executors of the estate of James Smiten Tripp,
deceased.*
